CLAIM

The ornamental design for the stink bait gun, as shown and described.

DESCRIPTION

FIG. 1 is a side perspective view of the stink bait gun showing my new design.

FIG. 2 is a side perspective view of the stink bait gun.

FIG. 3 is a side perspective view of the stink bait gun.

FIG. 4 is a side perspective view of the stink bait gun.

FIG. 5 is a rear perspective view of the stink bait gun; and,

FIG. 6 is rear perspective view of the stink bait gun.

The broken lines in the drawings are for the purpose of illustrating environmental features which form no part of the claimed design.
